[57] ABSTRACT

A method of forming a female flat garment form using a pair of paper sheets, a tape with adhesive on one side and means for securing the paper to the tape on the opposite side, and a plurality of markers formed generally in the same manner as the tape. The markers are first placed on the predominant bulges of the female after which the tapes are secured along the sides and shoulders. The paper sheets, one for the front and one for the back, are attached to the markers on the front and back of the female. The sheets are then fitted to the female by darts, as necessary, after which they are attached to the shoulder and side tapes. Subsequently the paper sheets are trimmed along the lines of attachment to the shoulder and side tapes, either after removal of the sheets, or prior to removal.

FLAT DRESS FORM

SUMMARY OF THE INVENTION

The present invention relates to a method of making a female flat garment form.

Another purpose of the invention is a kit including paper sheets, a tape for forming side and shoulder seams, and markers, all for use in fitting the paper sheets to the female figure.

Another purpose is a kit of the type described which may be reliably used by relatively inexperienced personnel.

Another purpose is a method of the type described which is relatively easy to perform and which reliably provides a female flat garment form shaped to a particular person.

Other purposes will appear in the ensuing specification, drawings and claims.

BRIEF DESCRIPTION OF THE DRAWINGS

The invention is illustrated diagrammatically in the following drawings wherein:

FIG. 1 is a diagrammatic illustration of the components of the kit disclosed herein,

FIG. 2 is a side view of a female figure with the markers and tapes applied thereto,

FIG. 3 is a front view of the female figure with the tapes and markers applied thereto,

FIG. 4 is a front view of the female figure after the paper sheets for forming the flat dress form have been applied thereto,

FIG. 5 is a perspective of one side of the tape,

FIG. 6 is a perspective of the opposite side of the tape,

FIG. 7 is a top perspective of one side of a marker, and

FIG. 8 is a plan view of the opposite side of the marker.

DESCRIPTION OF THE PREFERRED EMBODIMENT

The present invention relates to a method and kit for use in forming a flat dress form which is peculiar to a particular individual. The flat dress form may be placed underneath or used in connection with a commercial dress pattern to check the conformity of the commercial pattern to the particular individual's figure. Wherever the individual's figure is different from that used in forming the commercial dress pattern, the seamstress will be able to make appropriate changes before cutting the fabric.

The kit for use in making up the flat dress form includes a pair of paper sheets which are of a consistency such that they can be attached or hooked onto the tape. The sheets are indicated at 10 in FIG. 1 and should be of a size and shape to cover the average female figure and should be sufficiently pliable so that they may be effectively molded or fitted to the figure. A tape is indicated at 12 and is illustrated particularly in FIGS. 5 and 6. The bottom of the tape 12 may have an adhesive strip 14 which is used to apply the tape either directly to the skin or to an undergarment such as a body stocking, slip or the like. The top side of the tape may include a plurality of projections 16, preferably formed of plastic and having a rounded or unsharpened outer

end so as not to cause an injury to either the fitter or to the female being fitted. The projections 16 are preferably uniformly spaced and a spacing of one inch has been found to be practical in most applications.

5 The projections 16 may be attached to the tape in any suitable manner. There may be adhesive strips 18 and 20 and opposite sides of the projections 16 so as to assist in attaching the paper sheets 10 to the tape for use in forming the side and shoulder means of the garment or dress form.

A box 22 indicated in FIG. 1 may contain a plurality of markers 24 illustrated in FIGS. 7 and 8. Each of the markers may have an adhesive layer 26 on one side and a projection 28 on the opposite side. Preferably the projections 28 will be substantially identical with the projections 16 which are attached to the tape.

FIGS. 2-4, illustrate the method of forming a flat dress form with the kit components described above.

20 The female may either have a body stocking, as illustrated in FIGS. 2 and 3, or a suitable undergarment may be used during the fitting process. The markers 24 are attached to the female of the bulging areas such as the bust, seat, middle of upper back, thighs and 25 stomach. Tapes 12 are attached along each shoulder and along each side running from directly under the arm down to and including the hips. The adhesive layers on both the markers and the tapes are used to adhesively secure the same to the body without danger to 30 injuring either the body or the undergarment worn by the female being fitted.

After the markers and tapes have been required, the paper sheets 10 are applied to the front and back of the figure. In FIG. 4 the front sheet 10 has a dotted line 30

35 which is known as the grain line and which should be at the center of the figure and generally vertical. The back sheet will have a similar grain line. The front and back sheets are applied first to the markers, being suitably attached to the projections 28. The sheets then are 40 fitted to the figure by the use of folds or darts, where required, with the sheets then being attached, individually, to the tapes along the sides and shoulders. The tapes are passed over the projections and then

45 hooked onto the projections so that each of the front and back paper sheets are firmly attached to the tapes. The holes formed by the projections 16 mark the sheets so that they may be removed and trimmed along the shoulder and side seams. Generally the sheets should 50 be trimmed outside of the seams. Once the flat form has been thus completed, it can be used in conjunction with a commercial dress pattern to show what changes, if any, should be made in the pattern prior to cutting of the fabric. In this way, the fabric, once cut and sewn together, will properly fit the particular figure of the wearer.

Whereas the invention has been described in connection with a method in which the paper sheets are attached to projections on the tape it should be realized

60 that rather than projections the tape may consist of adhesive on both sides, with the sheets being attached to the adhesive and then a marker being used to indicate the side and shoulder seams. In like manner, the sheets may be trimmed while attached to the figure being fitted. There are many modifications to the invention, but what is important is to provide a means of molding or fitting paper sheets to a particular female figure in

such a way that after the sheets are trimmed, they provide a flat dress form peculiar to that person.

Although the invention has been described generally in connection with a dress, it should be understood that other female garments may be formed in like manner.

The invention should not be limited to markers or tape formed in precisely the manner shown. What is important is to provide means for securing the markers and tapes to the female figure and also for securing the paper sheets to the previously applied markers and tapes. The paper sheets should be sufficiently pliable so as to be fitted to the figure. They may have precut armholes or may be preformed in any other way as to materially reduce fitting time.

Whereas the preferred form of the invention has been shown and described herein, it should be realized that there may be many modifications and substitutions thereto.

I claim:

1. A method of making a female flat garment form using a pair of paper sheets, a tape having adhesive on

one side and means for securing the paper thereto on the opposite side and a plurality of markers having adhesive on one side and means for securing the paper thereto on the opposite side, including the steps of,

- 5 a. placing markers on the bulging areas of the female figure, such as the bust, thighs, seat, etc.,
- b. placing tapes along the shoulders, and sides of the female figure,
- c. placing a sheet of paper on the front and back of the female and attaching the sheets to the markers,
- d. adding darts, as necessary, to fit the paper sheets to the female figure,
- e. attaching the paper sheets to the shoulder and side tapes so as to fit the sheets to the figure, and
- f. trimming the paper sheets along the shoulder and side tapes.

2. The method of claim 1 further characterized in that attachment of the paper sheets to the shoulder and side tapes marks the paper sheets, with the further step

20 of removing the paper sheets prior to trimming.
